COMBINED TOWEL AND HANGER TAB

Robert Rohrs, 2650 SW. 87th Ave.,
Fort Lauderdale, Fla. 33394

Filed June 23, 1975, Ser. No. 589,419

Term of patent 14 years

Int. Cl. D6—13

U.S. Cl. D6—265

Fig. 1.

Fig. 2.

Fig. 3.

Fig. 5.

Fig. 4.

FIG. 1 is a front elevational view of a combined towel and hanger tab showing my new design;

FIG. 2 is a side elevational view thereof, the side opposite being a mirror image;

FIG. 3 is a top plan view thereof;

FIG. 4 is a bottom plan view thereof; and

FIG. 5 is a rear elevational view thereof.

I claim:

The ornamental design for a combined towel and hanger tab, substantially as shown and described.
